TRAY FOR REFRIGERATORS

Arthur W. Neel, Albany, Ind., assignor to McCormick Brothers Company, Albany, Ind., a corporation of Indiana

Application May 7, 1934, Serial No. 724,427

1 Claim. (Cl. 211—153)

This invention relates to improvements in trays which form fittings in household refrigerators. In such refrigerators, where the refrigerating unit is placed at one side of the refrigerating chamber, it is customary to arrange shelves or trays, one above the other, between said unit and the opposite wall of the chamber. Such trays are supported in various ways. One way of supporting the trays is to provide hooks in the back wall and one side wall of the refrigerating chamber upon which the trays may rest and to provide a leg depending from the front part of each tray, at the side next the refrigerating unit, which may rest upon a part of a lower tray. My invention relates to trays of the latter type. Such trays are usually made of several pieces welded together. In accordance with my invention, the frame of the tray, including a guard on the side of the tray next the refrigerating unit, and the supporting leg, are made from a continuous metal rod, the various parts or sections of the rod being formed so that the trays can be interchangeably mounted one upon the other. By this construction the trays are stronger and less expensive to manufacture than those heretofore in use.

In the accompanying drawing,

Fig. 1 is a front view of a refrigerator, partly broken away, showing two of the trays therein, in front view;

Fig. 2 is a perspective view of one of the trays, and,

Fig. 3 is a section on the line 3—3 of Fig. 1, showing the trays in side view.

Referring to the drawing, two of the trays, embodying my improvements, are shown at *a*, *a*, Fig. 1, at the right side of the refrigerating unit *b* in the refrigerator *c*. As shown in Fig. 2, each tray comprises a frame *a'* of rectangular form, having a depending leg *a²* at one side and near one of its front corners, and a suitable number of spaced strips or slats *a³* connected to the front and rear bars or sections of the frame. The frame *a'* and the supporting leg are formed from a continuous metal rod. A short end portion 1 of the rod forms part of one side section of the tray and from this part the rod is bent to form a front section 2, a side section 3 and a rear section 4, all of these parts of the frame being in a common plane. At the end of the rear section opposite the side section 3, the bar is bent upwardly as shown at 5 and thence extends horizontally forward to a point near the end of the part 1, forming a

guard 6 above the plane of the tray. At the forward end of the guard the rod is extended vertically downward, as indicated at 7, thence inclining forwardly, as indicated at 7^a, and thence extending vertically downward, beneath the part 1, as shown at 7^b, and terminating in a fork 7^c, these parts forming the leg *a²*, and the part 7 forming one end of the guard. The end part 1 of the rod is welded to the side of the part 7 and thus the guard and leg are securely fastened to the forward part of the frame.

In refrigerators a tray *d* usually extends across the interior of the refrigerator below the refrigerating unit. Each of the trays *a*, *a* rests on hooks 8 at one side of the refrigerating chamber and a hook 9 on the rear wall of the chamber and the forward corner of each tray next the refrigerating unit is supported by the leg depending from the tray, this leg resting upon a lower tray. Thus the leg of the lower tray *a* has its lower forked end resting upon the bar 10 of the long tray *d*, and the upper tray *a* has the forked end of its leg resting upon the part 1 of the tray *a* below it. The purpose of offsetting the lower part of the leg forwardly, by the inclined part 7^a, is to bring the forked end of the leg over the part 1 of a similar tray below it when the trays are assembled in a refrigerator.

The one-piece tray frame, guard and leg makes a stronger structure than is found in trays used for the same purpose composed of several parts welded together and this one-piece structure effects a saving in the cost of manufacture.

What I claim is:

A tray for the purpose described, comprising a frame and a supporting leg both composed of a continuous metal rod, said rod bent to form a rectangular frame comprising a front section, a side section, a rear section and a short end portion of the rod extending rearwardly from the front section and forming the front part of the opposing side section, the rear part of said opposing side section being offset upwardly from the rear section, thence extending forwardly to a point adjacent said end portion, forming a guard, said rod thence extending downwardly, forming a leg, the lower part of said leg being offset forwardly from the upper part thereof, and said short end portion of the rod being secured to said upper part of the leg.

ARTHUR W. NEEL.
